UNITED STATES PATENT OFFICE.

EARL L. PETERSON, OF CORONA, NEW YORK, ASSIGNOR TO UNITED CONCRETE PIPE COMPANY, OF NEW YORK, N. Y., A CORPORATION OF NEW YORK.

REINFORCED CONCRETE CONSTRUCTION.

1,346,673.

Specification of Letters Patent. Patented July 13, 1920.

Application filed January 6, 1920. Serial No. 349,676.

To all whom it may concern:

Be it known that I, EARL L. PETERSON, a citizen of the United States of America, residing at Corona, in the county of Queens, 5 Long Island, and State of New York, have invented certain new and useful Improvements in Reinforced Concrete Construction, of which the following is a specification.

My invention relates to reinforced concrete construction, and particularly to concrete pipe reinforced by an imperforate metal pipe embedded therein. Among the features of improvement secured by my invention are—

15 1st. Means for anchoring the concrete to the imperforate metal pipe;

2nd. Stiffening ribs secured to the imperforate pipe and reinforcing the latter;

20 3rd. Longitudinal ribs secured to the imperforate pipe and serving to space from the latter a mesh reinforce when the latter is used for additional reinforcement of the concrete;

25 4th. Ribs secured to the imperforate pipe and suitably shaped to engage and anchor the concrete in which they are embedded;

30 5th. Ribs secured to the imperforate pipe and shaped to receive the members, by which an associated mesh reinforce may be secured in position;

35 6th. A construction which embodies all of the aforesaid objects in a single type of rib secured to the imperforate pipe.

Various other features of improvement 40 will be hereinafter pointed out, or are shown in the accompanying drawings, in which,

45 Figure 1 is a longitudinal section through portion of a reinforced concrete pipe in which my invention is embodied in one form;

50 Fig. 2 is a transverse section therethrough drawn to a smaller scale;

55 Fig. 3 is an enlarged plan of portion of a metal pipe with associated mesh reinforce, but with the concrete casing omitted; and

Fig. 4 is a longitudinal section through the latter.

The present invention relates particularly 50 to that type of reinforced concrete conduit which comprises an imperforate metal pipe embedded in the concrete to render the conduit impervious to fluids or gases. In such a construction it is a difficult matter to secure a proper bond between the concrete

and the metal pipe, and unless such a bond is attained the concrete outer casing or inner lining is apt to crack and drop away from the metal pipe, thus exposing the latter. The object of the present invention is to provide means for anchoring the concrete to the pipe while at the same time maintaining the latter imperforate for the purpose above mentioned.

In the construction illustrated in the accompanying drawings, I have shown the metal pipe 5 embedded in the concrete, which thus forms an interior lining 6 and an exterior casing 7 therefor. To anchor the concrete to the pipe I have provided the latter with a series of circumferentially spaced longitudinally extending ribs 8 and 9 formed by angle irons. In order to maintain the pipe 5 imperforate, these ribs are welded thereto at longitudinally spaced intervals as indicated at 10, (Figs. 3 and 4). The manner of welding is immaterial, and in fact may be omitted if some other suitable means be employed to secure the ribs in place. For example, small brackets may be welded to the pipe and provided with claws beneath which the base of a T-shaped rib is engaged. Or the ribs may be held in position by a group of encircling or interior bands provided with positioning lugs to engage the ribs and hold the same in properly spaced relationship. It will be understood of course that where the construction of the conduit is such that an anchorage of the present type is not needed for both inner and outer faces of the pipe, it may be omitted from one or the other, without departing from my invention.

The ribs 8 and 9 are formed in any suitable way to mechanically engage and hold the concrete. A simple method of accomplishing this is to provide the same with perforations 11 through which the concrete passes when it is cast upon the pipe. The holes thus form anchorages in like manner 100 as an undercut rib, projections, or other suitable engaging elements on the ribs would, if the latter were so shaped.

When the pipe is to be subjected to considerable strain, either externally or internally, it is desirable to provide a further reinforce for the concrete in the form of a mesh. A common type of mesh reinforce is illustrated comprising circumferential rings or spiral wire rods 12 interconnected by 110

smaller wire net work 13. When such a reinforce is utilized with ribs, such as 8 and 9, the latter perform the very important function of spacing the mesh reinforce uniformly from the face of the pipe, and of affording ready means for anchoring the mesh in place. Thus, short tie wires 14 may be passed through the holes 11 in the webs of the ribs 8 and 9 and bound around the circumferential wire rods 12, thus holding the latter accurately in position and preventing their displacement during the casting of the pipe. Of course this anchorage of the mesh to the ribs 8 and 9 still further assists in binding the concrete in position and preventing it from breaking away from the metal pipe 5. Of course the mesh reinforce may be used either in the inner lining or in the outer casing of concrete, and it may be utilized on one face where the ribs are omitted, without departing from my invention.

It will be seen that the construction which I have described affords a reinforced concrete conduit in which the concrete lining and facing for the metal pipe are not only securely anchored to the latter, but the metal pipe itself stiffened by the longitudinal ribs 8 and 9, while the construction also affords the decided advantage of properly positioning and anchoring the mesh reinforce with respect to the metal pipe. Some of these advantages are extremely desirable even when the pipe is not maintained imperforate, and as to such advantages I do not wish my invention to be regarded as limited to an imperforate metal pipe.

While I have described my invention as applied to a conduit, and particularly a conduit for high pressure work, it is to be understood that the invention may be embodied in other types of concrete construction. Thus it may be embodied in tanks, chimneys, or other appropriate construction within the scope of my claim of invention, and it is to be understood that the terminology of the appended claims is used by me in a sense broad enough to cover such construction.

50 I claim—

1. A reinforced concrete conduit comprising an imperforate metal pipe embedded in

concrete, and longitudinally extending ribs mechanically attached directly thereto and serving to anchor thereto the concrete in which the metal pipe is embedded.

2. A reinforced concrete conduit comprising an imperforate metal cylinder embedded in concrete, and longitudinally extending ribs welded to the face of the pipe and serving to anchor thereto the concrete in which the pipe is embedded.

3. In a reinforced concrete conduit, a metal pipe embedded in concrete, longitudinal ribs mechanically attached directly thereto, and a mesh reinforce spaced by said ribs from the metal pipe.

4. In a reinforced concrete conduit, a metal pipe embedded in concrete, longitudinal spacing ribs mechanically attached directly thereto, and a mesh reinforce spaced by said ribs from the metal pipe, together with means for tying said mesh reinforce to the ribs.

5. In a reinforced concrete conduit, a metal pipe embedded in concrete, longitudinal spacing ribs mechanically attached directly thereto, and a mesh reinforce spaced by said ribs from the metal pipe, together with means for tying said mesh reinforce to the ribs, said ribs being shaped to afford a mechanical anchoring engagement with the concrete in which the pipe is embedded.

6. A reinforced concrete conduit comprising an imperforate pipe having longitudinal perforated ribs welded thereto, a mesh reinforce spaced by said ribs from the metal pipe, means for tying the mesh reinforce to the ribs, and concrete embedding said pipe, ribs and mesh reinforce, substantially as described.

7. A reinforced concrete conduit comprising a metal pipe embedded in concrete, independent, longitudinally extending, circumferentially-spaced, apertured ribs fastened directly to the exterior and interior of the metal pipe and serving to anchor to the latter the concrete in which it is embedded, in combination with an exterior mesh reinforce tied to said ribs and spaced thereby from the metal pipe.

In testimony whereof I have signed my name to this specification.

EARL L. PETERSON.
